UNITED STATES PATENT OFFICE

104,431

DESIGN FOR A COMBINED MILLING MACHINE COLUMN AND BASE

Joseph B. Armitage, Wauwatosa, Wis., assignor
to Kearney & Trecker Corporation, West Allis,
Wis., a corporation of Wisconsin

Application January 16, 1937, Serial No. 67,082

Term of patent 14 years

To all whom it may concern:

Be it known that I, Joseph B. Armitage, a citizen of the United States and resident of Wauwatosa, in the county of Milwaukee and State of Wisconsin, have invented a new, original, and ornamental Design for a Combined Milling Machine Column and Base, of which the following is a specification, reference being had to the accompanying drawings, forming part thereof.

Figure 1 is a view in side elevation of a combined milling machine column and base,

Figure 2 is a view in rear elevation of the combined milling machine column and base shown in Figure 1, and

Figure 3 is a view in perspective of the same combined milling machine column and base, showing my new design.

I claim:

The ornamental design for a combined milling machine column and base, substantially as shown.

JOSEPH B. ARMITAGE.
